CLAIM

The ornamental design for a stadium seat, as shown and described.

DESCRIPTION

FIG. 1 is a front view of a stadium seat of the present invention.

FIG. 2 is a rear view of the stadium seat of FIG. 1.

FIG. 3 is a top plan view of the stadium seat of FIG. 1.

FIG. 4 is a bottom view of the stadium seat of FIG. 1.

FIG. 5 is a right side view of the stadium seat of FIG. 1.

FIG. 6 is a left side view of the stadium seat of FIG. 1.

FIG. 7 is a front perspective view of the stadium seat of FIG. 1.

FIG. 8 is an enlarged sectional view in the direction indicated by the arrows 8-8 of the stadium seat of FIG. 1; and, FIG. 9 is an enlarged sectional view of the 9'-9' portion in the direction indicated by the arrows 9-9 of the stadium seat of FIG. 3.

The features shown in dotted lines depict environmental subject matter only and form no part of the claimed design. The broken lines having alternating long and short segments define bounds of the claimed design and form no part thereof.

1 Claim, 9 Drawing Sheets
